US00D904871S

(12) **United States Design Patent** (10) **Patent No.:** **US D904,871 S**
(45) **Date of Patent:** **** Dec. 15, 2020**

(54) **CLOSEABLE CARTON**

(71) Applicant: **Inno-Pak, LLC**, Delaware, OH (US)

(72) Inventors: **Jonathan D. Sill**, Delaware, OH (US);
Steven A. Mayer, Indianapolis, IN (US)

(73) Assignee: **Inno-Pak, LLC**, Delaware, OH (US)

(**) Term: **15 Years**

(21) Appl. No.: **29/633,127**

(22) Filed: **Jan. 12, 2018**

Related U.S. Application Data

(60) Continuation-in-part of application No. 29/573,421, filed on Aug. 5, 2016, now abandoned, which is a division of application No. 29/539,525, filed on Sep. 15, 2015, now Pat. No. Des. 774,893, which is a continuation of application No. 29/527,085, filed on May 15, 2015, now Pat. No. Des. 762,113, said application No. 29/633,127 is a continuation-in-part (Continued)

CLAIM

The ornamental design for a closeable carton, as shown and described.

DESCRIPTION

FIG. 1 is a perspective view of a first embodiment of the closeable carton, showing our new design;

FIG. 2 is a rear perspective view thereof;

FIG. 3 is a top plan view thereof;

FIG. 4 is a perspective view of a second embodiment of the closeable carton, showing our new design;

FIG. 5 is a rear perspective view thereof;

FIG. 6 is a front elevation view thereof;

FIG. 7 is a rear elevation view thereof;

FIG. 8 is a top plan view thereof;

FIG. 9 is a perspective view of a third embodiment of the closeable carton, showing our new design;

FIG. 10 is a rear perspective view thereof;

FIG. 11 is a top plan view thereof;

FIG. 12 is a perspective view of a fourth embodiment of the closeable carton, showing our new design;

FIG. 13 is a rear perspective view thereof;

FIG. 14 is a front elevation view thereof;

FIG. 15 is a rear elevation view thereof; and,

FIG. 16 is a top plan view thereof.

In the drawings, the broken lines are for the purpose of illustrating portions of the closeable carton that form no part of the claimed design.
